ROLLER SKATE

Charles O. Menzel, Milwaukee, Wis., assignor to Globe-Union Inc., Milwaukee, Wis., a corporation of Delaware

Application May 5, 1955, Serial No. 35,843

Term of patent 14 years

(Cl. D34—14)

FIG. 1

FIG. 2

FIG. 3

Fig. 1 is a view in side elevation of a roller skate, showing my new design;

Fig. 2 is a top plan view of such roller skate; and
Fig. 3 is an end view of such roller skate.

I claim:

The ornamental design for a roller skate, as shown.
